Primary Examiner — Paula Allen Greene(74) *Attorney, Agent, or Firm* — Altera Law Group, LLC(57) **CLAIM**

The ornamental design for a headset, as shown and described.

DESCRIPTION

FIG. 1 is a front elevational view of a headset showing my new design;

FIG. 2 is a bottom view thereof;

FIG. 3 is a top view thereof;

FIG. 4 is a left side view thereof;

FIG. 5 is a right side view thereof;

FIG. 6 is a back view thereof; and,

FIG. 7 is a perspective view thereof.

The features shown in broken lines depict environmental subject matter only and form no part of the claimed design.
